Patented Feb. 15, 1921.

Inventor:

Ate van der Schaaff.

64 *John J. Morris*
ATTORNEY.

UNITED STATES PATENT OFFICE.

ATE VAN DER SCHAAFF, OF Utrecht, NETHERLANDS.

TYPEWRITER.

1,368,865.

Specification of Letters Patent. Patented Feb. 15, 1921.

Application filed December 22, 1919. Serial No. 346,549.

To all whom it may concern:

Be it known that I, ATE VAN DER SCHAAFF, mechanician, a subject of the Queen of the Netherlands, residing at Utrecht, the Netherlands, J. P. Koenstraat 46b, have invented certain new and useful Improvements in Typewriters, of which the following is a specification.

The invention relates to an improvement 10 in typewriters and particularly to the provision of means whereby a type-head may be provided with a plurality of characters and adjusted in the printing operation, so that to utilize a selected one of such characters for printing.

The invention provides for the necessary coöperation of the parts without the usual bodily shifting of the carriage or type-bars, and to this extent provides for a construction which is lighter than the usual construction and which is capable of operation with less noise.

In the drawings:—

Figure 1 is a sectional view illustrative 25 of the construction.

Fig. 2 is a view of the guide and type-head therein.

The present improvement provides the usual type-bars 1 with type-heads 4, the heads 30 being pivotally connected to the bars at 5, and frictionally secured against undue play in such connection by springs 6. The fulcrum 2 for each type-bar is movable in the usual manner by a rod 3 connected to the 35 key lever, not shown.

The operative face of the type-head is curved in opposition to the curvature of the platen, and in the instance shown is provided with three separate characters arranged at such a distance apart that under 40 a slight turning of the head on its pivot 5, a particular one of such characters may be in printing position. To insure this operative movement of the type-head under the printing action of the type-bar, there is provided a guide 7 comprising a hollow shell shaped to receive each head as the latter is brought to printing position, and to accurately guide said head in its movement 45 into contact with the platen. The guide 7 is

mounted on pivots 8 supported in the frame of the machine and is formed with a depending arm 9 adapted to be engaged by an off-set 10 from the upper end of a rod 12. The rod is actuated to shift the off-set and thereby turn the guide in its pivotal support, through the medium of a lever 13 fixed on shaft 14, mounted in the machine and provided in turn with a lever 15, having on opposite sides thereof near the free 55 end, pins 16 and 17. For example, a finger lever 18 pivotally supported at 19, and limited in movement by stop 20 overlies pin 17 of lever 15, so that through operation of said lever 18 to guide 7 will be given a definite 60 pivotal movement and thereby positioned, so that the printing head engaged therewith will be accordingly shifted on its pivot to present the desired character for printing. The upper end of the rod 12 moves 65 over a fixed guide 11, and the extent of movement imparted to lever 15 by the finger levers arranged for such operation controls the position of the guide.

Having thus described the invention, what 70 is claimed as new is:—

1. A typewriter having a type bar, a type-head movably supported on said bar, and a pivotally supported guide to receive the type-head in the printing operation, said 75 guide having a depending arm, and means for engaging the arm to vary the pivotal position of the guide at will, whereby such change in the position of the guide will vary the movement of the type-head on the type-bar as said head passes into the guide in the printing operation.

2. A typewriter having a type-bar, a type-head pivotally supported thereon and formed with a plurality of type, a guide pivotally mounted on the machine and adapted to receive the type-head in the printing operation, an arm depending from said guide, and a finger operated bar to engage the arm and the guide on its pivotal 80 support to thereby position the guide to vary the pivotal relation of the type-bar and type-head in the printing operation.

In testimony whereof I affix my signature.
ATE VAN DER SCHAAFF.
